UNITED STATES PATENT OFFICE

146,787

DESIGN FOR A MARBLE-GAME TOY

Jess W. Carter and Arthur E. Saunders,
Los Angeles, Calif.

Application December 4, 1945, Serial No. 124,336

Term of patent 3½ years

(Cl. D34—15)

To all whom it may concern:

Be it known that, Jess W. Carter and Arthur E. Saunders, citizens of the United States, both residing at Los Angeles, in the county of Los Angeles and State of California, have invented a new, original, and ornamental Design for Marble-Game Toy, of which the following is a specification, reference being had to the accompanying drawing, forming a part thereof wherein

Figure 1 is a perspective view of a marble-game toy showing our new design, and Figure 2 is a rear elevational view thereof on a reduced scale.

I claim:

The ornamental design for a marble-game toy, as shown.

JESS W. CARTER.
ARTHUR E. SAUNDERS.
